LOCOMOTIVE SANDING APPARATUS

James E. Davenport, New York, N. Y., assignor to
The New York Central Railroad Company, a
corporation of New York

Application August 9, 1938, Serial No. 223,953

9 Claims. (Cl. 291—2)

This invention relates to certain new and useful improvements in sanding apparatus for steam and other locomotives.

One object of the invention is to provide means to cut out of action the sanding equipment so as to prevent use of sand by the engineman when the driving wheel speed due to slippage is greater than a predetermined value, and another object of the invention is to provide means to give the engineman a visible signal at a predetermined driving wheel speed due to slippage or to abnormally high train speed, to indicate that fact, which speed may or may not be the same as that at which the sanding equipment is automatically cut out. The apparatus thereby operates to prevent use of sand to stop slipping of driving wheels unless the driving wheel speed remains below the predetermined value, so as to require the engineman to stop the slipping by shutting off steam or by other suitable means until the driving wheel speed is reduced to a point below the predetermined value. The visual signal may also be used and so set as to indicate that the vehicle speed has reached a certain high value allowed, thereby warning the engineman to shut off or reduce the flow of steam.

The invention has special value and importance through these methods of sanding and speed control in preventing damage to the running gear of ultra high powered locomotives and ensuring the safer running of trains.

The sanding apparatus as herein disclosed is designed to be used in connection with a known type of speed indicating and recording device by which, through suitable means, the action of the sanding apparatus is automatically controlled, although it is to be understood that any other speed controlled device suitable for the purpose may be employed.

40 In the accompanying drawings,

Fig. 1 is a diagrammatic side elevation showing the application of general features of the invention to a locomotive.

Fig. 2 is a diagram of the electric circuit.

45 Fig. 3 is a horizontal section through the speed responsive or speed indicating and recording device.

Fig. 4 is a side view of parts shown in Fig. 3 looking toward the left from the right hand side thereof.

50 Fig. 5 is a section on the line 5—5 of Fig. 3.

Fig. 6 is a view in side elevation of a portion of the speed responsive or speed indicating and recording device shown in Figs. 3, 4 and 5.

55 Fig. 7 is a detail view of parts of the speed

responsive or speed indicating and recording device taken on line 7—7 of Fig. 3.

Referring now more particularly to the drawings, 1 designates a locomotive, 2 its drivers, 3 a sand dome, 4 and 5 sand traps, 6 and 7 the forward and reverse sanding pipes leading from the respective sand traps, 8 and 9 air feed pipes leading to the respective sand traps, 10 an air supply pipe leading from the main air reservoir or other source of supply of compressed air on the locomotive, and 11 a manually operable sander valve controlling the feed of air from pipe 10 to either of the pipes 8 and 9.

Disposed in pipe 10 is a solenoid valve 12 and disposed in the cab of the locomotive or at some other suitable point, so as to be in clear view of the engineman, is a pilot light or other visual signal 12'. These elements are included with control switches 13 and 14 therefor in an electric circuit 15 including also a turbo-generator 16 or other source of current supply. A condenser 17 is provided in the circuit for reducing arcing at the switch contacts. The switch 13 which controls the flow of current to the solenoid coil and the switch 14 which controls the flow of current to the pilot light may be or not of identical type. They may be for example of Burgess micro switch type embodying a spring contact blade 18 which is normally open and adapted to be moved to closed position by a push plunger 19 having a small range of movement for the purpose. Any other suitable type of switch may, however, be used.

Supported in contact with one of the drivers 2 is a friction wheel 20, and suitably supported on the locomotive is a speed responsive device 21 driven by a flexible shaft 22 from the wheel 20. This speed responsive device may conveniently be a Loco valve pilot type of speed indicating and recording device, such as generally comprehended by Wallbillich Patents Nos. 1,458,451 and 1,503,078, or any other type of speed responsive device suitable for the purpose. The device 21, for example, may include a centrifugal governor directly or indirectly driven by the shaft 22 and on the rotary shaft 23 of which slides a member 24 movable to different positions at different speeds and carrying actuating arms or levers 25 and 26 arranged to engage and operate the plungers 19 of the respective switches 13 and 14 at different assigned or predetermined locomotive speeds. The locomotive speed at which switch 13 is operated may be for example from 70 to 80 miles per hour, and the locomotive driving wheel speed at which the switch 14 is operated 90 miles per hour, or they

may be of any other predetermined relative sand cut off and signal indicating locomotive and driving wheel speeds.

As stated, the purpose of the invention is to prevent use of sand by the engineman when the driving wheel speed is greater than a predetermined value and to give the engineman a visible signal at a predetermined driving wheel speed which may or may not be the same as that at which use of sand is prevented. It may be assumed for example that it is intended to render the apparatus inoperative for sanding at a locomotive speed of 70 miles per hour and higher speeds and to give a visual signal to the engineman when the driving wheel speed whether or not corresponding to the locomotive speed reaches a predetermined maximum limit, say 90 miles per hour. The speed responsive device is set or adjusted for operation to close the switches 13 and 14 at these respective locomotive and driver wheel speeds.

Valve 12 is normally open at all speeds below the first-named speed of 70 miles per hour and therefore the engineman can operate valve 11 in one direction or the other from a normally closed position for either a forward or reverse sanding action as long as valve 12 remains open. At normal running speeds of an ultra power engine, which may be considered up to 70 miles per hour or thereabouts, the engineman can tell when the drivers are slipping by the exhaust from the engine, whereas he cannot do so at higher speeds because the exhaust is practically continuous. At the higher speeds, also, it is desirable to stop slipping by temporary reduction of power rather than by sanding which at very high or abnormal drive wheel speeds is liable by sudden sand checking of the driver wheel speeds to cause severe shocks and injury to the running gear. When, therefore, the speed responsive indicating and recording device reaches the 70 miles per hour point, or other speed point set, the arm or lever 25 engages and operates the plunger of switch 12 to close said switch, whereby solenoid valve 12 is closed to cut off communication between the air lines 8, 9, 10, and thus prevent feed of sand by operation of valve 11. Thus the engineman cannot feed sand to the track rails when the locomotive is running beyond the normal high speed limit of from 70 to 80 miles per hour or other predetermined locomotive speed or when the drivers are spinning excessively. If at any time the normal locomotive speed reaches the highest permissible limit set, i. e., 90 miles per hour, the speed responsive device is moved to bring arm or lever 26 into engagement with the plunger of switch 14 to close said switch and illuminate the pilot light 12', thus signalling the engineman that the locomotive is running at or above the highest permissible speed limit.

There is a critical high driver wheel speed during slipping at which it may be dangerous for the engineer to use sand because the sudden checking of the speed of these wheels from the critical high speed to train speed is liable to place the driving parts under compression and cause extreme shocks and damage to the drivers and other elements of the running gear. The driver wheel speed at which such shocks occur may vary in different types of ultra powered locomotives, but for purposes of exemplification herein, may be set at a minimum of 90 miles per hour driver wheel speed. It is also assumed, for example, that the locomotive or train limit speed normally allowed is set at from 70 to 80 miles per

hour and that the engineer may exceed this locomotive speed limit for practical operation under certain circumstances, and then only for short distances under safe track and other conditions. Engineers from their early days of training are instructed that taking a locomotive out of a slip by the use of sand is a dangerous practice, that the danger involved is greater the higher the slipping speed of the locomotive drivers, and that it is a safer practice to use the throttle to reduce train speed until the slippage stops before throwing sand if the use of sand should from any cause be required under such conditions. As stated, up to a locomotive running speed approximating 70 miles per hour the engineer is able to tell by the sound of the exhaust whether or not the drivers are slipping and to use his judgment as to whether or not to use sand when its use is ordinarily required. At a higher locomotive speed immediately around 70 miles per hour and higher, however, the engineer cannot from the exhaust tell when the drivers are slipping because the exhaust is practically continuous. At a locomotive speed higher than 70 miles per hour, also, the danger of sanding in case of driver slippage increases, because at such locomotive speed the driver speed, in case of slippage, may reach and greatly exceed the critical high driver speed of 90 miles per hour at which shocks and damages in the use of sand may occur. For this reason my invention is designed for preventing use of the sander at and above the prescribed high normal locomotive running speed of from 70 to 80 miles per hour, or a driver speed higher than 90 miles per hour, thus avoiding liability of shocks and damage to the running gear being caused in the event of sanding while the drivers are spinning at or above the critical high driving speed.

It is to be understood that the signal device employed gives an indication whenever the driver wheel speed reaches or exceeds the critical speed. As the locomotive is equipped with an indicating recording speedometer, and the engineer is able to tell by the sound of the exhaust at a train speed approximating 70 miles per hour whether or not the drivers are slipping, the engineer is positively advised upon the showing of the warning signal that one of two things is happening, either that he is operating his train considerably in excess of normally allowed train speed or that the locomotive has gone into a slip and its driver speed is in excess of the equivalent train speed under set conditions. This is also a warning that his sand control is cut off and that he is prevented from using sand under possibly dangerous conditions for the use of sand, and that he should at once use the throttle to cut down power for reduction of speed to normal running speed or to stop slippage. At train speeds materially below 70 miles per hour wheel slippage when occurring will ordinarily not reach the critical driver speed, but the engineer can tell from the exhaust whether or not slipping is taking place, and may use either sander or brakes to control train speed when emergency requires. At train speeds in the immediate region of 70 miles per hour, the driver speed in the event of slippage may reach the critical speed at times when the engineer may not be able to tell from the sound of the exhaust whether slippage is occurring. Under such conditions the signal will be actuated to positively tell the engineer that slipping at critical speed is occurring and that his sander is cut out so that he may take meas- 75

ures to reduce speed to take the locomotive out of the slip.

Each switch 13 and 14 comprises a suitable box or casing enclosing the switch blade or member 18. These boxes or casings are in practice bolted to the casing of the device 21, which may be provided with elongated openings for passage of the bolts and the switch plungers 19 so that the plungers may be adjusted as to position or set for their proper engagement by the arms or levers 25 and 26 at the determined locomotive speeds.

From the foregoing description, taken in connection with the drawings, the construction, operation and advantages of my invention will be readily understood without a further and extended description, and it will be obvious that it provides an apparatus which is simple of construction, reliable and efficient in action and economical in application and use. Where a speed indicator and recorder of the stated character or one of similar type is used, advantage may be taken of its use to employ it as a control device by modifications adapting it to operate the switches 13 and 14, but it is to be understood, of course, that any other suitable construction of speed responsive device may be used. It will also be understood that the speeds recited are given simply as examples, and that the switches 13 and 14 may be operated at any predetermined speeds desired. Furthermore, it is to be understood that while the structural organization shown is preferred, changes of various kinds, falling within the scope of the appended claims, may be made without departing from the spirit or sacrificing any of the advantages of the invention. While chiefly intended for use on steam locomotives the apparatus may also be employed on other types of power driven vehicles.

What I claim is:

1. In a sanding apparatus for vehicles having driver wheels, a source of fluid pressure supply, a manually operable valve normally effective for controlling the flow of fluid from said source for effecting a sanding action, and a driver wheel speed responsive device for preventing a sanding action on the operation of said valve at a driver wheel speed above a predetermined high driver wheel speed.

2. In a sanding apparatus for vehicles having driver wheels, means for controlling the action of a sander, means for preventing action of the sander at a predetermined high driver wheel speed, and driver wheel actuated means for indicating to the vehicle driver when the speed of the driver wheels has reached such predetermined speed.

3. In a sanding apparatus for vehicles having driver wheels, a source of fluid pressure supply, a manually operable valve normally effective for controlling the flow of fluid from said source for effecting a sanding action of the sander, an electrically operated valve controlling the flow of fluid from the source for preventing action of the sander by actuation of the manually operable valve, and a driver wheel speed responsive means for throwing the second-named valve into action at a driver wheel speed above a predetermined high driver wheel speed.

4. In a sanding apparatus for vehicles having driver wheels, a manually operable device for controlling the action of the sander, a device for

preventing action of the sander, a signal device for indicating that a predetermined high speed of the driver wheels due to conditions which produce slippage has been reached or exceeded, and speed responsive means actuated by the driver wheels controlling the second and third named devices.

5. In a pneumatically operated sander for vehicles having driver wheels, a manually operable valve normally effective for controlling the pneumatic operation of the sander, a cut off valve for preventing the pneumatic operation of the sander, and a driver wheel driving speed responsive means for actuating said valve for a cut off action at a driver wheel speed above a predetermined high driver wheel speed.

6. In a pneumatically operated sander for vehicles having driver wheels, a manually operable valve normally effective for controlling the pneumatic operation of the sander, a cut off valve for preventing the pneumatic operation of the sander, a signal device for indicating when a high driver wheel speed due to conditions which produce slippage is reached or exceeded, and a driver wheel driven speed responsive means for actuating the valve for a cut off action and operating said signal device at a driver wheel speed above the predetermined high driver wheel speed.

7. In a sander for vehicles having driver wheels, a manually operable device normally effective for controlling the action of the sander, an electrically operated device for preventing operation of the sander, an electric circuit including said electrically operated device, and a driver wheel driven speed responsive means controlling said circuit to energize said electrically operated device at a driver wheel speed above a predetermined high driver wheel speed.

8. In a sander for vehicles having driver wheels, a manually operable device normally effective for controlling the action of the sander, an electrically operated device for preventing operation of the sander at a driver wheel speed above a predetermined high driver wheel speed, an electrically operated device for giving a signal when a predetermined high driver wheel speed is reached, or exceeded, an electric circuit including said devices and switches for controlling the circuit to energize the same, and a driver wheel driven speed responsive means for controlling said circuit to energize said electrically operated devices at driver wheel speeds above the first-named predetermined high driver wheel speed.

9. In a compressed air operated sander for vehicles having driver wheels, sand delivery pipes, a source of air supply, a manually operated valve normally effective for controlling the flow of air from said source to effect discharge of sand through the pipes, an electrically operated valve solely controlling the flow of air from the source to the manually operable valve for cutting off the supply of air to the pipes and rendering the manually operated valve inoperative for a control action, and a driver wheel driven speed responsive means controlling the flow of electric current to energize the electrically operated valve at a driver wheel speed above a predetermined high driver wheel speed.

JAMES E. DAVENPORT.
